UNITED STATES PATENT OFFICE

1,968,873

STARTING AND STOPPING MECHANISM

Alfred S. Clark, Beverly, Mass., assignor to United Shoe Machinery Corporation, Paterson, N. J., a corporation of New Jersey

Application November 7, 1932, Serial No. 641,539

10 Claims. (Cl. 192—144)

This invention relates to a starting and stopping mechanism and is illustrated as embodied in a machine particularly adapted for use in inserting paper pegs in the manufacture of boots and shoes, although it may conveniently be used in many other types of machines.

The invention is illustrated as used in a paper peg inserting machine of the type illustrated and described in U. S. Patent No. 1,802,900, granted April 28, 1931 on an application filed in the names of Fred N. La Chapelle and Fred C. Eastman, and it was designed especially to be substituted for the starting and stopping mechanism shown and described in said patent. In fact, many of the parts used in the starting and stopping mechanism of that machine are utilized in the illustrated machine, which constitutes a preferred embodiment of the present invention.

20 It is the object of the invention to improve and simplify starting and stopping mechanisms of, for example, the type used in the LaChapelle and Eastman machine and to make the adjustment of the same not only easier but more reliable.

With the above object in view, a feature of the invention consists of a block which is moved in opposite directions in substantially a constant path, which is substantially a straight line, by a driven part of any machine in which the present invention may be incorporated. This block is arranged to be either effective or ineffective to transmit motion between said driven part of the machine and a mechanism 30 which controls a clutch and a brake. The block is made ineffective to transmit the above motion because of a lost-motion connection arranged thereon and, when it is necessary for the block to transmit positive motion between the above-mentioned parts, the lost motion is taken up by a take-up mechanism. Preferably, and as illustrated, this take-up mechanism consists of an abutment lever mounted on the block. This abutment lever may be locked so that the block 40 will be effective to transmit positive motion or it may be unlocked so that the block is yielding and ineffective to transmit this motion. When the abutment lever is unlocked, the usual clutch spring in the machine acts to release the brake and engage the clutch to drive the machine. On the other hand, when the abutment lever is locked, the block is effective to transmit positive motion from the driven part of the machine in a direction to disconnect the clutch and apply the brake.

Another feature of the invention comprises a release lever for the locking lever which is arranged to be automatically disconnected from the locking lever after the clutch has been tripped so that the locking lever will operate 60 during the first revolution of the machine to lock the abutment lever and cause the driven part of the machine to operate through the block to disconnect the clutch and apply the brake at the completion of one revolution. If 65 desired, this feature of the invention, relating to the automatic disconnection of the release lever from the locking lever, may be omitted so that the release lever will hold the locking lever out of contact with the abutment lever as long 70 as the operator wishes the machine to run. The machine is then stopped at the will of the operator by withdrawal of the release lever to normal position, which permits the abutment lever to become locked and the machine to be 75 stopped in the same manner as when the mechanism is operating as a one-revolution clutch, in the manner above described.

With the above and other objects and features in view, the invention will now be described 80 in connection with the illustrated machine and will be pointed out in the accompanying claims. The invention is not limited for use in the particular type of machine herein illustrated but is only limited as defined in the appended claims. 85

In the drawings, Fig. 1 is a view showing a portion of the machine of the LaChapelle and Eastman patent with the improved starting and stopping mechanism of the present invention substituted for the 90 corresponding mechanism used in that machine; the parts being shown in the position that they occupy when the machine has been stopped by the mechanism;

Fig. 2 is a detail of the mechanism just after 95 the machine has been tripped and before the machine has actually started to move;

Fig. 3 is a detail, similar to Fig. 2, but with the parts of the mechanism in an intermediate position;

Fig. 4 is a detail, similar to Fig. 2, but with the parts locked, or in the position shown in Fig. 1; and

Fig. 5 is a detail of a modified construction, 105 with the parts in the position that they occupy while the machine is being driven continuously.

Only as much of the LaChapelle and Eastman machine will be described as is necessary for a complete understanding of the invention. It should be noted that the machine, when equipped 110

with the improved starting and stopping mechanism of the present invention, operates in the same manner as described in said patent.

Suitably journaled in the head of the machine 5 is a shaft 50 (Fig. 1) having fast upon its forward end a group of cams preferably formed as a unit and indicated by the numeral 52. Fast upon a sleeve 54 rotatably mounted upon the shaft 50, but secured against endwise movement, 10 is a clutch member 56 to which is rigidly secured a beveled gear 58 meshing with a beveled gear 34 by which the clutch member is driven. Slidably but non-rotatably mounted upon the shaft 50 is a clutch member 60 having a clutch face 15 62 arranged to be moved into and out of engagement with the adjacent face of the clutch member 56 and a brake surface 64 correspondingly moved out of and into engagement with a stationary brake surface 66 formed upon the 20 head of the machine. To prevent the clutch member 60 from rotating on the shaft 50, the forward end of the clutch member is provided with a plurality of projections 68 telescoping with corresponding projections 70 formed 25 upon the rear of the cam member 52 and thus fast upon the shaft 50. Clutch member 60 is also formed with a collar 72 forming an abutment at the rear end of a stiff coiled spring 74 surrounding projections 68 and 70 and bearing 30 at its forward end against a plane surface formed upon the rear of the cam member 52, the spring 74 thus tending to move the clutch member 60 rearwardly into power transmitting position. 35 Threaded upon and rigidly clamped to the clutch member 60 is a collar 76 to the rear of which is a hub 78. By means of the threads, the collar and its hub may be adjusted axially of the clutch member 60. The hub 78 is provided with a pair of pins 80 on opposite sides of the shaft 50 which engage hooks formed on the upper end of a lever 82 fulcrumed at 84 to the head of the machine. Thus, when the lever 82 is held in the position shown in Fig. 1, the 40 spring 74 is compressed and the clutch member 60 is maintained in its forward or non-power transmitting position while, when the lever 82 is rocked, by mechanism hereinafter described, in a counter-clockwise direction from the position of Fig. 1, the clutch member 60 is moved rearwardly by the force of the spring 74 into engagement with the continually driven clutch member 56 and thus becomes effective to transmit power to the cam member 52. 45 The above reference characters are the same as those used in the LaChapelle and Eastman patent, to which reference should be made for a description of the parts relating to the fastener-inserting mechanism. 50 The illustrated machine is arranged to be started by upward displacement of a nozzle 100 accomplished by pressure of the work against the nozzle. For this purpose the nozzle 100, which is mounted for vertical slidable movement, carries a pin 102 positioned in a slot formed in the forwardly extending arm 103 of a bell-crank lever 104 fulcrumed at 106 on the head of the machine. An upwardly extending arm 107 of the bell-crank lever 104 is connected by an adjustable link 108 to the upwardly extending arm 110 of a second bell-crank lever 112 fulcrumed at 114 on a movable block 126. The bell-crank lever 112 has a horizontally extending arm 127, the purpose of which will presently be described. 55 The block 126 is moved back and forth by a

rod 128 sliding in ways in the head of the machine and operated by a cam 130, cut in the cam member 52, and a cam roll 132 mounted on the rod 128. The rear end of the block 126 is provided with a slot 140 which forms a lost-motion connection with a pin 142 (which corresponds to the pin 250 of the LaChapelle and Eastman patent) mounted in the lower end of the lever 82. 80

Briefly outlining the construction about to be described, and referring to the drawings, it should be noted that, with the block 126 held in fixed position, (as is the case when the machine is in stopped position) lost-motion of the pin 142 in the slot 140 will permit the lower end of the lever 82 to move forward (to the right in the drawings) under the influence of the spring 74, to release the brake and engage the clutch to start the machine. On the other hand, if the block 126 has been carried forward by the 95 cam 130, (as is the case after the machine has been started) and a fixed abutment is then positioned in the forward end of the slot, subsequent movement of the block 126 to the rear will move the lever 82 to disengage the clutch and 100 apply the brake.

In order to provide means whereby the pin 142 and slot 140 may, at times, have lost-motion relatively to one another and, at other times, have this lost-motion taken up and a fixed abutment placed in the forward end of the slot, the rear end of the block 126 is provided with a vertical groove so that two rearwardly extending forks are formed, between which an abutment lever 150 is pivotally mounted at 152. The upper end of the abutment lever 150 is continuously maintained in engagement with the pin 142 by a plunger 154 mounted in the block 126 and pressing against the abutment lever 150 by means of a spring 156 inserted in a bore in the 115 block 126 behind a shoulder on the plunger 154.

To lock the abutment lever 150 so that movement of the block to the rear will be transmitted through the pin 142 to the lever 82, a locking lever 158 is pivotally mounted at 160, between 120 the rearwardly extending forks of the block 126. This locking lever 158 is urged upwardly by a spring 162 connected between a pin 164 on the locking lever and a pin 166 mounted in the block 126. When the rod 128 is moved to the 125 rear it carries with it the block 126 and, as the pin 142 is then stationary, the spring-pressed plunger 154 rotates the abutment lever in a counterclockwise direction so that the lower end of the abutment lever moves to the right and 130 permits the locking lever 158 to move upwardly, by its spring 162, behind the abutment lever 150 and lock it against clockwise rotation. This position of the parts is shown in Fig. 4, with a notch 168 near the forward end of the locking 135 lever in engagement with the lower end of the abutment lever 150. Lost motion is thus taken up and the block 126 is now effective to transmit positive motion from the rod 128 to the pin 142 when the rod 128 is moved to the rear. This 140 movement of the block 126 to the rear thus carries the pin 142 with it, from its dotted line position in Fig. 4 to the position shown in section, and the upper end of the lever 82 is moved to the right to disengage the clutch and apply the 145 brake.

The machine, as stated above, is started by an upward displacement of the nozzle 100, which motion is communicated through mechanism previously described, to give a downward move- 150

ment to the arm 127 of the bell crank lever 112, which is pivotally mounted on the block 126. To the arm 127 is pivotally attached a release lever 170, which is arranged to start the machine 5 in the following manner:

The lower end of the release lever 170 is provided with a surface 172 which, in the stopped position of the machine (Fig. 4) is located immediately above a projection 174 on the locking 10 lever 158. Downward movement of the bell-crank arm 127, (produced by lifting the nozzle 100), carries the release lever downwardly and the engagement of the surface 172 with the projection 174 carries the locking lever 158 downwardly to carry its notch 168 out of engagement with the lower end of the abutment lever 150, thus unlocking the abutment lever. With the lower end of the abutment lever unlocked, the pin 142 is free to move to the right in the slot 140, from its dotted line position in Fig. 2 to the position shown in section, because the force of the spring 74 is sufficient to overcome the slight resistance of the spring-pressed plunger 154 against the abutment lever 150. Thus the lever 25 82 swings counterclockwise under the influence of the spring 74 to release the brake and engage the clutch to start the machine.

When it is desired to have the machine make only one revolution at a time, the release lever 30 is provided with a cam surface 176 which is arranged to engage a projection 178 on the block 126. As the release lever is carried downwardly (by upward movement of the nozzle 100), the cam surface 176 disengages the lower 35 end 172 of the release lever 170 from the projection 174, just after the abutment lever 150 has been unlocked, so that the locking lever is free to move upwardly under the influence of its spring 162 until it meets the lower end of 40 the abutment lever 150. This position of the mechanism is shown in Fig. 3. As the machine is now in operation, the cam 130 is carrying the rod 128 and block 126 forwardly, so the abutment lever 150, being maintained in contact with 45 the pin 142 by the spring pressed plunger 154 is rotating counterclockwise. This soon allows the locking lever to move upwardly and permit its notch 168 to lock the abutment lever, as shown in Fig. 4.

It should be noted that the locking lever 158, with this arrangement, is always lifted to lock the abutment lever, irrespective of the manipulation of the nozzle 100 in tripping the machine, because the rod 108 is either moving to the rear or is substantially fixed in position at the time the tripping occurs and the rod 128 is moved forward by the cam 130, thus the pivot 114 of the bell-crank lever 112 is moved forwardly, rotating the bell-crank lever still further in a counterclockwise direction so that its arm 127 is further depressed, carrying the release lever 170 always downwardly a sufficient distance for the cam surface 176 to disconnect the release lever 170 from the locking lever 158. Thus the release lever can never interfere with the return upward movement of the locking lever 158 under the action of its spring 162.

In order that the cam surface 176 and projection 178 may be effective to operate as above described, the release lever is urged to the rear by a tension spring 180 stretched between the pin 166 and a pin 182 secured to the lower end of the release lever 170.

When it is desired to incorporate the present 75 invention in a machine which is driven for a

number of revolutions and is stopped only at the will of the operator, a release lever 170^a is provided without the cam surface 176. Such a construction is illustrated in Fig. 5. Under such circumstances, the arm 127 of the bell-crank lever 112 would be moved downwardly by movement of the adjustable link 108, which, instead of being connected to a nozzle, would be connected to any suitable operator-controlled device, such as a treadle, and would be held in this position as long as the operator wishes the machine to run. The release lever would thus hold the locking lever 158 out of engagement with the abutment lever 150 during this period, as shown in Fig. 5. When the operator desires to stop the machine, the arm 127 would be raised, by the operator-controlled means, and would carry with it the release lever 170^a. The locking lever 158 would follow it to a raised position behind the abutment lever, locking the abutment lever and causing the machine to stop at the completion of that revolution, as hereinbefore described.

It will be noted that, with the present invention, the only adjustments necessary are, first: the adjustment of the adjustable link 108 for length so that upward movement of the nozzle 100 will be more or less sensitive to trip the machine, and second: the adjustment of the collar 76 to cause the lever 82 to operate the clutch member 60 with the desired motion to obtain suitable action of the brake.

Having thus described my invention, what I claim as new and desire to secure by Letters Patent of the United States is:—

1. A connection for controlling a clutch and brake mechanism comprising a block, means at one end of the block for connecting it to a reciprocating part of a machine, means at the other end of the block for connecting it to a clutch and brake mechanism, these means acting to cause the block to move in substantially a straight line only, and means mounted on the block for rendering the block either a yielding or a non-yielding connection between the reciprocating part of the machine and the clutch and brake mechanism.

2. A connecting mechanism for controlling a clutch and brake, having, in combination, a block, means for moving the block in opposite directions in substantially a constant path, an abutment member mounted on the block, means to render the abutment member either yielding or non-yielding whereby, when it is rendered yielding, it will permit the brake to be disengaged and the clutch to be engaged and, when it is rendered non-yielding, movement of the block in one direction will cause the clutch to be disengaged and the brake to be applied.

3. A connecting mechanism for controlling a clutch and brake, having, in combination, a block, means for moving the block in opposite directions, an abutment member mounted to move in opposite directions relatively to the block, means acting to either prevent or permit such relative movement, the abutment member acting, when such relative motion is permitted, to permit the brake to be disengaged and the clutch to be engaged, and acting, when it is prevented, to cause movement of the block in one direction to disengage the clutch and apply the brake.

4. A connection for controlling a clutch and brake mechanism comprising a block, an abutment lever pivotally mounted on the block,

spring operated means for swinging the lever into yielding abutting position, a locking lever, a spring for bringing the locking lever into position to lock the abutment lever in unyielding 5 position, a release lever for moving the locking lever out of locking position, a bell crank lever pivotally mounted on the block and carrying the release lever, and means under control of the operator for swinging the bell crank lever to 10 operate the release lever.

5. A connection for controlling a clutch and brake mechanism comprising a block, an abutment lever pivotally mounted on the block, spring operated means for swinging the lever 15 into yielding abutting position, a locking lever, a spring for bringing the locking lever into position to lock the abutment lever in unyielding position, a release lever for moving the locking lever out of locking position, a cam for disengaging the release lever from the locking lever after 20 the locking lever has been moved out of locking position, a bell crank lever pivotally mounted on the block and carrying the release lever, and means under control of the operator for swinging 25 the bell crank lever to operate the release lever.

6. A mechanism for controlling a clutch and brake comprising a block, a joint at one end of the block for connecting it to a moving part of 30 a machine, a joint at the other end of the block for connecting it to a clutch and brake mechanism, one of said joints having lost-motion, take-up means mounted on the block for taking up the lost-motion to permit movement of the 35 moving part of the machine to be transmitted to the clutch and brake mechanism for stopping the machine, and means to restore the lost motion condition to the one of said joints.

7. A mechanism for controlling a clutch and 40 brake comprising a block, a joint at one end of the block for connecting it to a part of a machine which is movable in opposite directions, a joint at the other end of the block for connecting it to a clutch and brake mechanism, one of 45 said joints having lost-motion, and take-up means mounted on the block for taking up the lost-motion upon movement of the block in one direction so as to permit movement of the block in the opposite direction to transmit motion to 50 the clutch and brake mechanism to disconnect the clutch and apply the brake.

8. A mechanism for controlling a clutch and 55 brake comprising a block, a joint at one end of the block for connecting it to a part of a machine which is movable in opposite directions, a joint at the other end of the block for connecting it to a clutch and brake mechanism,

one of said joints having lost-motion, take-up means mounted on the block for taking up the lost-motion upon movement of the block in one direction so as to permit movement of the block 80 in the opposite direction to transmit motion to the clutch and brake mechanism to disconnect the clutch and apply the brake, and means to start the machine by rendering the take-up means inoperative.

9. A connecting mechanism for controlling a clutch and brake having, in combination, a clutch and brake controlling lever, a block, means for moving the block in opposite directions, an abutment lever pivotally mounted on the block, spring operated means for swinging the abutment lever against the controlling lever, a locking lever, a spring operating when the block is moved in one direction to bring the locking lever into position to lock the abutment lever in unyielding position whereby, when the block is moved in the other direction, positive motion will be transmitted from the block moving means to the clutch and brake controlling lever to disengage the clutch and engage the brake, a release lever for moving the locking 100 lever out of locking position to permit the clutch and brake controlling lever to release the brake and engage the clutch, and means under control of the operator for operating the release lever.

10. A connecting mechanism for controlling a clutch and brake having, in combination, a clutch and brake controlling lever, a block, means for moving the block in opposite directions, an abutment lever pivotally mounted on 110 the block, spring operated means for swinging the abutment lever against one end of the controlling lever, a locking lever, a spring operating when the block is moved in one direction to bring the locking lever into position to lock the 115 abutment lever in unyielding position whereby when the block is moved in the other direction positive motion will be transmitted from the block moving means to the clutch and brake controlling lever to disengage the clutch and engage the brake, a release lever for moving the locking 120 lever out of locking position to permit the clutch and brake controlling lever to release the brake and engage the clutch, a cam for disengaging the release lever from the locking 125 lever after the locking lever has been moved out of locking position, a bell-crank lever pivotally mounted on the block and carrying the release lever, and means under control of the operator for swinging the bell-crank lever to operate the 130 release lever.

ALFRED S. CLARK.
